UNITED STATES PATENT OFFICE.

ANDREW SMITH, OF CHICAGO, ILLINOIS.

DESIGN FOR A CLOTHES-PIN.

SPECIFICATION forming part of Design No. 35,442, dated December 17, 1901.

Application filed November 13, 1901. Serial No. 82,161. Term of patent 7 years.

To all whom it may concern:

Be it known that I, ANDREW SMITH, a citizen of the United States, residing at Chicago, in the county of Cook and State of Illinois, 5 have invented and produced a new and original Design for Clothes-Pins; and I do hereby declare the following to be a full, clear, and exact description of the invention.

My invention relates to a novel design for 10 a clothes-pin, the object being to provide a new and ornamental design of a pin for this purpose.

The accompanying drawing shows a perspective view of a clothes-pin embodying my 15 design.

My design consists in a four-sided pin bifurcated at one end, said bifurcation extending somewhat more than one-half of the length of the pin and being widened as it 20 approaches the end of the pin on a graceful curve, thus forming two prongs, which terminate in rounded wedge-shaped ends. The opposite end of said pin is surmounted by a four-sided head, whose lateral faces are

rounded and are in line with the sides of the 25 body of the pin. The body of the pin adjacent the head is contracted on a graceful curved outline for about a quarter of the length of the pin and being smallest and about one-half the thickness of the body of 30 the pin where the same joins the head. A small narrow transverse strip or projection somewhat shorter than the width of the pin is placed on each of two opposite sides of the pin adjacent the head end of said bifurcation. 35

This design is effective and very pleasing in appearance.

I claim as my invention—

The design for a clothes-pin, substantially 40 as shown and described.

In testimony whereof I affix my signature in presence of two witnesses.

ANDREW SMITH.
